Primary Examiner — John Windmuller(74) *Attorney, Agent, or Firm* — Barlow, Josephs & Holmes, Ltd.(57) **CLAIM**

The ornamental design for a flexible support arm, as shown and described.

DESCRIPTION

FIG. 1 is a perspective view of the flexible support arm in accordance with the invention;
 FIG. 2 is a front view thereof;
 FIG. 3 is a rear view thereof;
 FIG. 4 is a right side view thereof;
 FIG. 5 is a left side view thereof;
 FIG. 6 is top view thereof;
 FIG. 7 is a bottom view thereof; and,
 FIG. 8 is front perspective view thereof in use, the dashed lines forming no part of the claimed design.
